CLAIM

The ornamental design for a tomato plant cage, as shown and described.

DESCRIPTION

FIG. 1 is a perspective view of a tomato plant cage, showing my new design.

FIG. 2 is a front elevation view thereof, the rear, left side, and right side elevation views being identical thereto;

FIG. 3 is a second perspective view thereof;

FIG. 4 is a perspective view of a second embodiment thereof, consisting of two (2) tomato plant cages, each of which is identical to the tomato plant cage shown in FIGS. 1-3;

FIG. 5 is a front elevation view of a third embodiment thereof, consisting of twelve (12) tomato plant cages, each of which is identical to the tomato plant cage shown in FIGS. 1-3; and,

FIG. 6 is a front elevation view of a fourth embodiment thereof, consisting of ninety-six (96) tomato plant cages, each of which is identical to the tomato plant cage shown in FIGS. 1-3.
